UNITED STATES PATENT OFFICE.

ADOLPH P. GUSTAFSON, OF CHICAGO, ILLINOIS, ASSIGNOR TO M. SCHULZ COMPANY, OF CHICAGO, ILLINOIS.

PNEUMATIC REGULATOR.

1,250,104.

Specification of Letters Patent. Patented Dec. 11, 1917.

Application filed September 21, 1914. Serial No. 862,663.

To all whom it may concern:

Be it known that I, ADOLPH P. GUSTAFSON, a citizen of the United States, residing at Chicago, in the county of Cook and State 5 of Illinois, have invented a certain new and useful Improvement in Pneumatic Regulators, of which the following is a full, clear, concise, and exact description, reference being had to the accompanying drawings, 10 forming a part of this specification.

My invention relates to pneumatic regulators or governors for automatically regulating pneumatic pressure.

Prominent objects of the invention are 15 to provide a simple and practical type of regulator; to secure sensitiveness and accuracy in regulation; to reduce the number of parts and obtain simplicity in construction; to secure reliability of action and prevent 20 sudden action which would produce irregular operation of a device depending on the governor, and to secure the foregoing and other desirable results in a simple and practical manner.

25 In the accompanying drawings Figure 1 is a vertical section of a pneumatic regulator or governor embodying my invention taken on line 1—1 in Fig. 2;

Fig. 2 is a section taken on line 2—2 in 30 Fig. 1;

Fig. 3 is a section taken on line 3—3 in Fig. 1; and

Fig. 4 is a section taken on line 4—4 in 35 Fig. 3.

The regulator shown comprises a stationary member 1 which is understood to be suitably mounted or fixed in any desired position as by securing it to a vertical upright or support 2. A movable or swinging member 3 is secured to the member 1 by a 40 hinge connection 4. A swinging block or lever 5 is pivoted between side blocks 6—6, a pin 7 serving to pivot the swinging member 5 in position between the blocks 6—6, the latter being secured to the swinging member 3 by screws 8—8. A spring 9 is secured to the swinging member 5 as by screws 10—10, said spring 9 extending upwardly and making contact as at 11 (Fig. 1) with the fixed 45 member 1. The swinging member 3 of the pneumatic carries a screw 12 whose inner end 13 is adapted to come into contact with the member 5.

A block 14 is secured to the base member 1 50 and provided with side ports 15—15 and

also with an interior chamber 16 communicating with said ports and also communicating with a duct or passage 18 which is understood to lead to the wind inducing apparatus. A valve device 20 is pivoted as by a 60 screw 21 to the side of the block 14, the valve 20 thus controlling the ports 15—15. Said valve 20 is provided with a projection 20^a which is adapted to come into contact with the swinging member 3 of the pneumatic or bellows whereby said member 3 tends to act upon and actuate said valve member 20. A small wire spring 22 is desirably provided tending to hold the valve member 20 in a right hand position, (Fig. 70 1), that is a position to hold the ports 15—15 open. A duct or passage 25 is provided from the interior of the pneumatic to some other port or chamber or device whose wind supply is to be regulated. As shown, this duct 75 or passage 25 leads to another chamber 26 in the device, which chamber 26 contains a valve 27 operated by a hand or other rod 28, as desired, the arrangement shown being such as may be employed in connection with 80 a motor which might be connected with the tube or pipe 29.

Thus it will be seen that the pneumatic pressure will be automatically regulated by the device, the bellows member 3 operating 85 to act upon the valve 20 and more or less close or open the ports 15—15. When there is increased tension, or in other words further reduction of air pressure communicated to the passage 18, the pneumatic will naturally be collapsed further, thereby causing the member 3 thereof to act upon the valve 20 and cause a further closure of one or more of the ports 15—15. This will thereby allow a less amount of communication through 90 95 said ports of a greater degree of tension, thereby reequalizing the increased tension. Conversely when a tension communicated to the passage 18 is reduced, the member 3 will tend to move outwardly or expand, 100 thereby permitting the valve 20 to open the ports 15—15 farther, and thereby allowing a greater communication to be established by such reduced pressure, whereby equalization may be effected. It will be seen that the 105 screw 12 by acting upon the swinging member 5 and by having the spring 9 of considerable relative length, will give a very desirable and satisfactory sensitiveness of action, the leverage of the member 5 and 110

spring 9 being such as to bring this about. It will also be seen that by having the valve 20 acted upon by the member 3, the sensitiveness and accuracy may be further increased, the adjustment of the valve effecting only moderate opening and closing action upon the ports 15—15, whereby the opening and closure of said ports will be well graduated, permitting a small amount of opening and closing to take place. Also by having a plurality of ports 15 this sensitiveness and accuracy is increased. Also by having said ports opened in a sidewise manner and having the valve 20 open and close them by a knife-like or shearing movement as opposed to a separating movement, further advantage in adjustment and regulation is secured. By having the valve 20 pivoted as a lever and acted upon by the member 3 such adjustment as is desired may be secured, it being obvious that the regulation or position of the valve lever 20 and its pivot with reference to the member 3 and the point thereon where said valve lever makes contact, may be arranged as desired to suit various conditions and circumstances. The adjusting screw 12 may be adjusted from the outside of the device so as to vary the tension of the spring 9.

It will be understood that changes and modifications may be made without departing from the spirit of the invention.

What I claim is:

1. A pneumatic regulator comprising a collapsible device having a movable member, a spring located within said device and acting upon said movable member to prevent collapse of the device, means for regulating the tension of said spring, said means extending through the wall of said movable member so as to be operable from the outside of the same, and a valve and valve seat provided with a port controlled by said valve, said valve being arranged for actuation by said movable member.

2. A pneumatic regulator comprising a collapsible device having a movable member, a spring located within said device and arranged to act to prevent collapse on the part of said device, a screw extending through the wall of said device and arranged to control the tension of said spring, and a valve and ported valve seat located within said device and arranged to be actuated by said movable member.

3. A pneumatic regulator comprising a pneumatic having a swinging member, a

spring located within said pneumatic and combined with an adjusting screw passing through said swinging member and coöperating with a pivoted block within the pneumatic to control the tension of said spring, a pivoted valve located within the pneumatic and having a projection contacting with said swinging member, and a valve seat provided with ports arranged to be controlled by said valve.

4. A pneumatic regulator comprising a collapsible device having a movable member, a spring located within said device, a swinging member interposed between said spring and said movable member, an adjustable abutment carried by said movable member and contacting with said swinging member, and a valve lever pivoted within said collapsible device and contacting with said movable member.

5. A pneumatic regulator comprising a collapsible device having a movable member, a spring located within said device, a swinging member interposed between said spring and said movable member, an adjustable abutment carried by said movable member and contacting with said swinging member, a valve lever pivoted within said collapsible device and contacting with said movable member, and a block also arranged within said collapsible device and provided with a plurality of ports controlled by said valve.

6. A pneumatic regulator comprising a collapsible pneumatic having a movable member, an adjusting screw passing through said member, a swinging member carried by the movable member of said pneumatic and contacting with the inner end of said adjusting screw, a valve spring located within said pneumatic and extending lengthwise underneath said movable member whereby said movable member acts upon said spring, a block provided with a plurality of side ports, a pivoted lever arranged lengthwise of the movable member of the pneumatic and having a projection contacting with the inner surface thereof, said lever being arranged to open and close said ports in said block in a shearing manner, and a spring controlling said valve lever.

In witness whereof, I hereunto subscribe my name this 15th day of September, A. D. 1914.

ADOLPH P. GUSTAFSON.
